Warren E. Willis.
ATTORNEY

UNITED STATES PATENT OFFICE

ABRAHAM SPRUNG, OF NEW YORK, N. Y., ASSIGNOR TO MUNICIPAL STREET SIGN CO., INC., OF NEW YORK, N. Y., A CORPORATION OF NEW YORK

STREET SIGN

Application filed July 25, 1929. Serial No. 380,845.

This invention relates to signs and more particularly to metal signs as displayed at street intersections in which a legend bearing plate is held within the confines of a support frame.

Quite commonly the sign plate is enamelled in colors, contrasting with the lettering, and rigidly held to a support; under such unyielding conditions variations of contraction and expansion occur, due to changes in temperature, tending to crack the enamel, disfigure the sign and allow moisture to attack the metal backing, causing rust and ultimate destruction to take place.

Furthermore the ordinary frame embossed sign is unnecessarily expensive, due to the structural fastening means employed and devices by which angular positional adjustment is obtained relative to the streets.

It is therefore an object of the present invention to provide a sign having an enamelled plate loosely but securely held within a unitary frame, capable of independent contraction and expansion whereby cracking and peeling of the enamel is almost entirely avoided, and its edges protected.

A further feature is in the provision of means whereby single or superposed signs may be adjusted at any desirable relative angle and positively held against displacement.

Another purpose is to produce a sign of unusual simplicity, having a minimum number of parts and which presents an attractive appearance.

These advantageous objects, and others of like nature, are accomplished by the novel design, construction and combination of parts as herein described and shown in the accompanying drawings, in which:

Figure 1 is a perspective view of the upper portion of a double sign as made in accordance with the invention.

Figure 2 is a partial side elevational view of the upper part of a double sign, the lower sign being in transverse section and showing its attachment to a support.

Figure 3 is a sectional view taken in line 3—3 of Fig. 2.

Signs of this character are usually sup-

ported on posts set permanently in the ground, the post in the present instance being preferably an upright hollow tube 10 having its top cut squarely across.

Seated on the upper end of the tube is a flat circular cap 11 having a downwardly extending arcuate flange 12 at its edge suited to engage around approximately half the diameter of the tube and provided with lugs 13 at its ends.

On the opposite side of the tube is a correspondingly arcuate clamp 14 having end lugs 15 to match the lugs 13 forming pairs clamped by bolts 16 whereby the device is securely and rigidly fixed upon the post which is thus covered by the cap 11.

Formed integrally on the upper surface of the cap 11 is a bar 17 extending an equal distance horizontally outward from the center to perpendicular elements 18 connected by another horizontal bar 19 parallel and integral with the lower bar 17 and forming a unitary frame.

The frame elements 17 and 18 contain in their inner surfaces, centrally of the widths of the bars, a continuous narrow channel or circuitous groove 20 of uniform depth and width and in the upper member 19 is a central longitudinal slot or bifurcation 21 opening communicating with the channel in the end members 18 of the integral frame.

Raised from the sides of the bar 19 is a circular boss 22 split lengthwise by a continuation of the slot 21 into two equal portions, which may be clamped by bolts 23 passing through lugs 24 on the boss, these lugs extending along the upper edges of the split bar 19 as shown.

The boss 22 contains a frusto-pyramidal recess 25 extending in from the top to an annular space 26 the bottom of which is level with the upper edge of the bar 19 and it is to be noted that the base of the recess 25 is directed downwardly, thus presenting convergent walls; obviously the recess may be frusto-conical if preferred, and it is apparent that the sides of the socket may be spread to admit entrance of the plug due to yielding of the bifurcated frame elements 19—19' by reason of their longitudinal slots 21.

Disposed in the recess 25 is a solid plug 27, tapered in accordance with the interior walls of the recess and which may be provided with opposed lugs 28 suited to engage in annular space 26.

5 The plug 27 may be integral with the flange 29 of an ornamental finial 30, if a single sign is to be exhibited, or if a double sign is desired the plug may be formed on the edge of the lower element 17' of the superposed frame, which in other respects is a duplicate of the frame previously described and to which prime numbers are appended.

15 Sign plates 31 of the usual enamelled type are inserted into the frames, singly and enamelled on one or both sides but usually in pairs, through the slots 21 to loosely engage in the channels 20 and are positively held therein by the plugs 27, the sign plates being 20 of lesser dimensions than the distances between opposite channels and extend upward into the slot 21 so that their edges are completely concealed.

25 In the bottoms of the channel in the lower bar of the frame are perforations 32 to permit the drainage of water which might otherwise collect therein and cause the frame and plates to rust.

30 Due to the conicity of the plugs 27 and sockets 25 either plain or of polygonal cross section, a wide range of relative adjustability is obtained, and by reason of inverted taper of the plugs and sockets, the upper frame or finial is positively rigidly held therein upon 35 tightening the bolts 23, in addition to engagement of the lugs 28 within the recess 26, the frames are relatively radially adjustable and the lower frame may be turned at any angle upon the axis of the post 10.

40 From the foregoing it will be seen that a simple device for this purpose has been disclosed in the preferred form of its embodiment, but it is not desired to restrict the details to the exact construction shown, it being 45 obvious that changes, not involving the exercise of invention, may be made without conflicting with the scope of the appended claims.

Having thus described the invention, what is claimed as new and desired to secure by

50 Letters Patent, is:—

1. A sign comprising a unitary metal frame having a bifurcated upper member and interiorly channelled end and lower members, one or more legend plates engageable in the 55 channels through the upper member, a boss on the upper member formed equally on each side of the bifurcation, said boss containing a frusto-conical recess in its base directed toward the frame, a plug engaged in the recess, and means for clamping the plug therein.

60 2. A sign comprising a unitary metal frame having a bifurcated upper member and interiorly channelled end and lower members, one or more legend plates engageable in the 65 channels through the upper member, a split

boss integral with the upper member, said boss having an axial opening and an annular recess therewithin, a plug engaging in the opening, lugs on said plug to engage in the annular recess, and means for clamping the 70 boss upon said plug.

3. A sign comprising a unitary metal frame having a bifurcated upper member and interiorly channelled end and lower members, one or more legend plates engageable in the channels through the upper member, a split boss integral with the upper member, said boss having a frusto-pyramidal socket therein with outwardly convergent walls, a plug to engage said socket and means 80 for clamping the socket upon said plug.

4. A sign comprising an integral oblong rectangular frame having an interior circuitous groove in its end and lower elements and a longitudinal slot through its upper element 85 in open communication with the groove, a legend bearing plate enterable vertically through the slot to loosely engage in the groove by gravity, a split boss centrally of the members of said upper element and a 90 plug engaged in said boss to retain said plate within the frame.

5. A sign comprising an integrally cast frame having a circuitous channel in its interior and a slot in its upper member connecting the ends of the channel, the channel and slot being in the same plane, a split boss integral with said upper member, a legend plate to freely pass into the channel through the slot and boss, a plug removably engaged 100 in said boss to retain said plate within the frame, and clamp bolts on each side of the boss.

6. A sign comprising a unitary metal frame having a continuous channel in the inner edges of its end and lower members and a through reaching, longitudinal passage in the upper member connecting the channel ends, a sign plate adapted to enter the channel through the passage, a plug to confine 110 said plate within the channel, and means operative to clamp the side elements of said upper member against said plug, said side elements being resilient.

7. A sign comprising two independent 115 frames arranged in superposed relation, said frames having circuitous interior grooves and sign plates therein, the lower of said frames having a longitudinal opening in its upper member, a tapered plug and socket 120 connection between said frames, said socket being yieldable to permit entrance of the plug, said plug having its greatest diameter at its extremity, and means for clamping the plug rigidly when adjusted in the socket.

8. A sign comprising a pair of independent unitary frames, sign plates in each frame, a tapered plug and socket connection of polygonal cross section permitting relative axial adjustment between said frames,

said plug having its largest diameter at the outer end, clamping means for said connection, a finial clamped on the upper frame, and means for adjustably clamping the lower

5 frame upon a support.

9. A sign comprising a unitary frame having channelled bottom and side members and a top open midway its length to receive one or more sheet metal signs therethrough,

10 means for draining said channel, a post, a flat circular plate covering said post integral with the lower member of said frame, a pair of semi-circular clamps to surround the top of said post, one of said clamps being integral with said plate to constitute the bottom of the frame and the other separable, said separable clamp contacting the underside of said plate, and means to secure the clamps on said post.

15 20 In testimony whereof I affix my signature.

ABRAHAM SPRUNG.
